UNITED STATES PATENT OFFICE.

OTTO S. THAL, OF SAN FRANCISCO, CALIFORNIA.

COMBINATION GUIDE AND DIRECTOR.

1,326,116.

Specification of Letters Patent.

Patented Dec. 23, 1919.

Application filed May 14, 1918. Serial No. 234,525.

To all whom it may concern:

Be it known that I, OTTO S. THAL, a citizen of the United States, residing at San Francisco, in the county of San Francisco and State of California, have invented new and useful Improvements in Combination Guides and Directors, of which the following is a specification.

This invention relates to a combination 10 guide and director for drawing letters and figures.

One of the objects of the present invention being to provide a simple, cheaply manufactured combination guide and director, which may be employed for amusement or other purposes, said device comprising a slotted card adapted to be pivotally mounted or slidably moved over a surface upon which it is desired to make a transcription, 20 said card being also provided with a means for directing the movement of the card, whether it is pivotally or slidably mounted.

Another object of the invention is to provide a device of the character described, 25 which may be used as a postal card, and which cannot be deciphered or read without leaving a visible indication, thus preventing unauthorized persons from reading the card.

Further objects will hereinafter appear. 30 The invention consists of the parts and the construction and combination of parts as hereinafter more fully described and claimed, having reference to the accompanying drawings, in which—

Figure 1 is a view of one form of the device.

Fig. 2 is a plan view of another form of the device.

Referring to the drawings in detail:

A indicates the card, on one end of which is formed a slot 2. Arranged on one edge of the card, as shown at 3, is a plurality of directing numerals, and arranged on one side of the slot, as at 4, is another set of directing numerals. The card when used is pivotally attached to a surface upon which it is desired to make a transcription; for instance, as shown in Fig. 1, a thumb tack is inserted through the card A at one corner 45 and the card B upon which the transcription may be made.

The transcription is accomplished in the following manner:

With the card A pivotally attached to 55 the card B, it is first necessary to make a mark C upon the card B. The card A is

then moved until the arrow 5 registers with the mark C, mark C being made at any point upon the card B desired.

The next operation is to insert a pencil in 60 the slot 2 at the point marked X. The pencil is then moved from X downwardly along this slot until it reaches the numeral 1. It is then moved upwardly along this slot until the numeral 2 is reached, the next 65 number appearing in the succession is 3. This is found among the first set of numerals printed on the edge of the card, and it indicates that the card must be moved until the numeral 3 reaches the point marked C 70 on card B.

The last move of the pencil was from 1 to 2 along the slot. It is held at this point while the card is being moved about the pivot until the numeral 3 reaches the point marked C. 75

The operator will next find that two numerals will appear, *i. e.*, the number 4 and the numeral 4^a. This means that 4^a must be brought into register with the mark C, and 80 that the pencil must be moved downwardly from 2 to 4 in the slot while the card is being swung from the number 3 to the number 4^a. This causes the formation of an angular line. The pencil is held at the point 4 in 85 the slot, and the card is again swung until 5 registers with the mark C on the card B. The pencil is next moved upwardly along this slot into alinement with number 6. It is held at this point while number 7, which 90 is the next number in succession, is moved into register with the point C.

We again find two numerals of a similar character, *i. e.*, 8 and 8^a. This means that the pencil must be moved downwardly from 95 the point 6 in the slot to the point 8, and that the card must simultaneously be moved from number 7 until 8^a registers with the mark C. The pencil, after this movement has been made, is held in alinement with 100 number 8 in the slot, and the card is next swung until the numeral 9 registers with the mark C. To continue the operation, it is necessary to move the pencil upwardly along this slot until it alines with the number 105 10, as this is the succeeding number.

We again find two numerals, *i. e.*, number 11 and 11^a. The pencil must, therefore, be moved from 10 to 11 in the slot, and the card must at the same time be swung about 110 its pivot until 11^a registers with the mark C. The pencil is retained in the slot at the point

11, and the card is again swung until the numeral 12 registers with the mark C. It is then moved down the slot until it alines with the numeral 13, and the whole operation is finally completed by swinging the card until the numeral 14 registers with the mark C.

By removing the card A from the card B, and inspecting the transcription made, it 10 will be found that the operator has written the word "Fool." Any word may be written in this manner by arranging the different sets of numerals to suit the word, and practically any design or figure may be 15 drawn by the same method.

It is, therefore, obvious that a card constructed as here shown and operated in the manner herein described may prove a great 20 source of amusement, both for children and grown, and that it may also be used for transmitting secret messages and for other purposes.

One use of the device to which it may be successfully and commercially applied, is 25 the postal card service. The slot 2 should in that instance be arranged in one corner so that it may be covered by the stamp when mailed. It would thus be impossible for any one but the person to whom the card 30 is addressed to decipher or transcribe the same as it would be necessary to break the stamp before it would be possible to insert the pencil in the slot. It would also be necessary to puncture one corner of the card 35 to pivotally attach it to the card upon which it is desired to make the transcription, thus leaving two visible indications. No one but the person to whom the card is 40 addressed can, therefore, read or transcribe the word or message contained without visibly showing that such transcription has been made.

Another form of the card is shown in Fig. 2. This card is also slotted as at 2^a, 45 and provided with directing numerals along two edges as shown. This card may be placed on any ordinary card and moved along one edge of the same; all vertical lines being made in the slot, and all horizontal lines being made by moving the card lengthwise, the movements being indicated 50 and limited by the numerals along the outer edge and the slot, angular lines being drawn in a manner similar to that previously described, and every operation being the same.

While the device as here illustrated is a postal card, it is obvious that it may take any form desired; for instance, it may be

cut in the shape of a figure or ornamental design, and it is, therefore, capable of being modified in many ways.

The materials and finish of the device may be such as the experience and judgment of the manufacturer may indicate.

I wish it understood that various changes 65 in form, proportions, and minor details, may be resorted to within the scope of the appended claims, and that I do not wish to limit myself to the specific design and construction here shown.

Having thus described my invention, what I desire to secure by Letters Patent is—

1. A combination card and director, comprising a card, having an opening formed therein for the reception of the pencil, and two sets of directing numerals formed on the card to indicate movement of the pencil in the opening and movement of the card while the pencil remains stationary in the opening.

2. A device of the character described, comprising a card, having a slot formed therein, a plurality of directing numerals arranged on one side of such slot, and a second set of directing numerals arranged along one edge of the card, said slot adapted to receive a pencil to guide the same, and said numerals adapted to direct the movement of the pencil in the slot and also movement of the card proper.

3. A device of the character described, comprising a card, having a slot formed therein, a plurality of directing numerals arranged on one side of such slot, a second set of directing numerals arranged along one edge of the card, said slot adapted to receive a pencil to guide the same, and said numerals adapted to direct the movement of the pencil in the slot and also movement of the card proper, and means for pivotally 100 mounting the card.

4. A combination card, said card having a guide formed thereon for the reception of a pencil and for the guidance thereof, and two sets of directing numerals formed on the card to indicate the movement of the pencil in the guide, and movement of the card while the pencil remains stationary in the guide.

In testimony whereof I have hereunto set 110 my hand in the presence of two subscribing witnesses.

OTTO S. THAL.
